UNITED STATES PATENT OFFICE.

CHARLES R. SHORT, OF DETROIT, MICHIGAN, ASSIGNOR TO GENERAL MOTORS COMPANY, OF DETROIT, MICHIGAN, A CORPORATION OF NEW JERSEY.

GUIDE MEMBER FOR VALVE-OPERATING MECHANISM OF INTERNAL-COMBUSTION ENGINES.

Application filed April 6, 1917. Serial No. 160,128.

To all whom it may concern:

Be it known that I, CHARLES R. SHORT, a subject of the King of Great Britain, and resident of Detroit, Wayne County, State of Michigan, have invented certain new and useful Improvements in Guide Members for Valve-Operating Mechanism of Internal-Combustion Engines, of which the following is a specification.

10 This invention relates to hydrocarbon motors, and more particularly to improvements in guiding a resonant reciprocating member in a guide sleeve, whereby noise is prevented by any lateral movements between the member and the sleeve.

In previous reciprocating valve operating mechanisms where a metallic member reciprocates in a metallic sleeve, an undesirable noise or clicking has been produced when there is any quick lateral movement between the member and the sleeve, such as after the clearance between these parts has been increased above the normal allowances by wear. Wherever rocking members such as cams are used for reciprocating the valve operating members with a resultant lateral thrust component, the difficulty experienced is considerable and very objectionable, producing undesirable noises or clicks.

25 To obviate these and other difficulties, and to greatly improve the construction, efficiency and operation of a motor reciprocating valve mechanism, my invention has been provided.

30 The various objects will more clearly appear from the following description taken in connection with the accompanying drawings which form a part of this specification and in which:

35 Figure 1 is an end view, with portions in section, of a hydrocarbon motor power plant, embodying preferred forms of my invention; and

40 Figure 2 is a longitudinal vertical section through the center of a non-metallic guide sleeve.

45 Referring to the drawings, 10 illustrates a motor crank case, having a cylinder block 11 formed thereon. A shaft 12 provided with cams 13 is adapted to be supported in bearings 14 in the crank case. The block is provided with a head 15 having a port 16 which is adapted to be controlled by a poppet valve member 17. The stem 18 of

the metallic valve member is adapted to be 55 reciprocally mounted in a metallic guide sleeve 19 which is inserted through an opening 20 in the head, with its shoulder 21 resting against the upper portion thereof. A metallic bearing is shown between the 60 lower end of the sleeve 19 and the stem 18. The upper part of the sleeve is counter-bored for a short distance from its top as shown at 22 and a non-resonant bushing 23 preferably formed of fibre is adapted to be 65 inserted between the recess portion 22 of the guide sleeve and the upper end of the valve stem 18.

A collar 23' is secured to the upper end of the valve stem and a spring 24 is arranged between the collar and a disc 25 for yieldingly closing the valve member on its port seat. A rocker arm 26 is trunnioned as at 27 on the cylinder head with its curved shoe 28 in contact with the upper end of the 75 valve stem. The opposite end 29 of the rocker arm may be adjustably connected as by a coupling 30 to the upper end of an operating rod 31.

The lower end of the operating rod 31 is 80 connected in any well known manner to a metallic tappet 32 mounted in a pair of non-resonant bushings 33, preferably of fibre and supported in opposite ends of a sleeve 34 which is fitted on the crank case. 85 The contact shoe 35 which is arranged at the lower end of the tappet is adapted to be thrust upwardly by the cam 13.

It will be noted that as the cam rotates it will tend to thrust the lower end of the tappet member laterally as it is pushed upwardly and it will be understood that this movement will tend to gradually increase the normal clearance between the lower end of the tappet member and the bushing. If 90 the contact were between metal and metal, it would obviously set up an annoying noise or click, at every reverse movement. With the non-resonant contact provided, this difficulty is entirely overcome.

Between the upper end of the valve stem and the guide, where there is a similar tendency to produce a lateral thrust movement, a similar device for eliminating any undesirable noise is provided.

Referring particularly to Figure 2, it will be noted that I have illustrated an entire guide sleeve 19' as illustrated at 22

in Figure 1, formed of a non-resonant material, such as fibre instead of metal as is usually the case.

I am aware that a soft fibrous material 5 has been used as a lining for a guide for reciprocating members mounted therein to prevent the squeak which might occur when one member rubbed the other in passing. I am also aware that fibre has been used to 10 receive and partially cushion the end impact of metallic members, and I therefore do not broadly claim the use of a non-metallic material in this respect, the essential feature of the invention being the simple and efficient means for absorbing the 15 shock and deadening the noise peculiar and incident to the "side slap" where a reciprocal member is mounted in a guide and intermittently operated by a cam or other member 20 which tends to transmit a lateral movement to the reciprocal member whereby side stresses are set up.

While I have described and will specifically claim what I deem to be preferred embodiments of my invention, it will be 25 obvious to those skilled in the art, that various modifications and changes may be made without departing from the spirit and scope hereof.

Having thus described my invention, what 30 I claim and desire to secure by Letters Patent is:

In an internal combustion engine, the combination with a metallic guide sleeve having a stepped inner periphery, a reciprocating metallic valve member mounted therein and periodically subjected to lateral stresses, and a hard wear resisting non-metallic bushing pressed into the stepped portion of said guide sleeve to receive the 40 shocks due to said lateral stresses.

In testimony whereof I affix my signature.

CHARLES R. SHORT.
